Inventor

JOHN H. PATTEN

By his Attorney

Richard T. Cook

UNITED STATES PATENT OFFICE.

JOHN H. PATTEN, OF SEATTLE, WASHINGTON.

DESIGN FOR A VEHICLE-TIRE.

57,376.

Specification for Design.

Patented Mar. 15, 1921.

Application filed July 15, 1920. Serial No. 396,619. Term of patent 7 years.

To all whom it may concern:

Be it known that I, JOHN H. PATTEN, a citizen of the United States, and resident of the city of Seattle, county of King, and State of Washington, have invented a new, original, and ornamental Design for Vehicle-Tires, of which the following is a specification, reference being had to the accompanying drawing, forming part thereof.

Figure 1 is a plan view of a portion of the tread of a vehicle tire.

Fig. 2 is a sectional view on the line 2—2 of Fig. 1.

I claim:

The ornamental design for a vehicle tire, as shown.

JOHN H. PATTEN.
